CENTRIFUGAL SPINNING BUCKET

Henry Crewdson, Chester County, Pa., assignor to
American Viscose Corporation, Wilmington,
Del., a corporation of Delaware

Application April 30, 1943, Serial No. 485,144

2 Claims. (Cl. 57—76)

This invention relates to improvements in centrifugal buckets useful for twisting and collecting natural or artificial filaments or yarns or for liquid treating or hydroextraction of liquid-treated wound packages or cakes formed or placed therein. It is particularly an improvement in one of the forms of centrifugal bucket shown in my copending application Serial No. 433,155, filed March 3, 1942. As shown in Figure 7 of my copending application, the motor may be provided with a hollow spindle for driving the centrifugal bucket and a rod reciprocable within the hollow spindle and terminating at its upper end in a flat plate which forms a supporting base for the package or cake within the centrifugal bucket. This plate serves to eject the cake after the handling, such as collecting, liquid-treating, or hydro-extracting, within the centrifugal bucket is finished, such ejection being effected by means of cams operating upon a plate secured to the base of the reciprocable rod. Alternatively, as shown in Figures 4 to 6 of that application, a reciprocable cake-supporting plate is provided with a plurality of depending rods which extend through corresponding openings in the bottom of the centrifugal bucket and carry therebeneath an annular plate by which the actuation effected by cam means is transmitted through the rods to the cake-supporting plate in the centrifugal bucket to eject the cake.

The use of a hollow shaft for driving the centrifugal bucket operates satisfactorily but has the disadvantage that because of the high speed at which the centrifugal bucket is normally operated, special care must be taken in manufacturing the hollow shaft to assure that it is balanced perfectly. Otherwise, severe strains and excessive vibrations are developed during operation of the centrifugal bucket. On this account, the manufacture of hollow shafts for this purpose is an expensive procedure. On the other hand, the other form of device has the disadvantage that the plurality of rods depending through the openings in the bottom of the centrifugal bucket create excessive windage and involve an excessive consumption of power for operation.

In accordance with the present invention, an improvement is provided by which the windage and power losses occasioned by the latter form of device of my copending application are overcome. Other advantages of the invention will be apparent from the description thereof for which reference should be made to the drawing, in which:

Figure 1 is an elevation in cross-section of the improvement, with the ejector device in the position that it normally occupies during operation of the centrifugal bucket.

Figure 2 is a similar elevation in cross-section showing the ejector device in the position corresponding to the ejection of the cake, and

Figure 3 is an elevation of a modification.

As shown, a motor 2 arranged with its rotating spindle vertical drives a centrifugal bucket 3 carried thereon by means of a hub 4 fitting over the upper end of the spindle 5. The bucket may be of any standard form used for twisting and collecting, liquid-treating and liquid-extracting purposes and it may be provided with the conventional liquid-escape perforations in the walls and with a cover and cover-locking device of conventional construction. A cake-supporting member in the form of a plate 6 normally rests against the bottom of the centrifugal bucket during operation thereof as shown in Figure 1 and is provided with depending rods 7 which are symmetrically disposed about the center thereof. These rods 7 are secured to the under side of the plate 6 or they may be integral therewith and extend through a corresponding number of symmetrical openings 8 through the bottom of the bucket. The lower ends of the rods are secured to an annular plate 9 whose under surface is adapted to cooperate with any suitable lifting means 10. The rods 7 may be of any desired length, preferably being sufficiently long to effect complete ejection of the wound package or cake within the spinning bucket without causing the lower plate 9 to strike the bottom of the bucket. A sleeve 11 having an internal diameter at least as large as the extremal diameter of the body of the bucket is secured to the plate 9 carried by the rods 7 and in the position shown in Figure 1 is of sufficient height to substantially inclose the space between the bottom of the bucket and the plate 9, thereby preventing the development of windage and excessive power consumption because of the beating of the air by the rods 7. Preferably, the plate 9 is provided with a bearing 12 which cooperates with the spindle 5 of the motor to steady the whole structure. This bearing 12 is arranged to be sufficiently below the hub 4 of the spinning bucket 3 in the normal operating position (Figure 1) so that it will not strike the hub when the ejection device is moved into the ejecting position shown in Figure 2.

The cam or other means 10 for actuating the ejector device may take any suitable form and may be operated by hand or automatically upon

the completion of the treatment of the cake within the spinning bucket whether that treatment be twisting and collecting, liquid-treating, or liquid-extracting. Thus a vertically reciprocable rail 13 may be arranged to extend beneath the annular plate 9 of the ejector device of a plurality of centrifugal buckets associated with a machine for spinning artificial filaments in which the buckets serve to twist and collect the filaments in the form of a wound cake so that a plurality of such spinning buckets may be doffed at once. Alternatively, the motors and centrifugal buckets may be carried through a cyclic path along one portion of which they pass a stationary means for actuating the ejection devices of the respective buckets individually as shown in my co-pending application.

While a preferred embodiment of the invention has been shown, it is to be understood that changes and variations may be made without departing from the spirit and scope of the invention as defined by the appended claims.

I claim:

1. In apparatus for handling filamentary material, a rotatable shaft, a centrifugal bucket

thereon, a cake-supporting member within the bucket, a plurality of rods extending from the member and reciprocable through apertures in the bucket bottom, an annular member carried by the rods outside the bucket and a sleeve carried by the annular member having an internal diameter at least as large as the external diameter of the body of the bucket substantially inclosing the space between the bucket bottom and the annular member.

2. In apparatus for handling filamentary material, a rotatable shaft, a centrifugal bucket thereon, a cake-supporting member within the bucket, a plurality of rods extending from the member symmetrically arranged with respect to the shaft and reciprocable through apertures in the bucket bottom, an annular member carried by the rods outside the bucket, a sleeve carried by the annular member having an internal diameter at least as large as the external diameter of the body of the bucket substantially inclosing the space between the bucket bottom and the annular member and a bearing carried by the annular member for cooperation with the shaft.

HENRY CREWDSON.
